VINCENZO LOMBARDI CERRI, OF AVEZZANO, ITALY

SOUND-PROOF CASE FOR TYPE-WRITING MACHINES.

1,111,477.

Specification of Letters Patent. Patented Sept. 22, 1914.

Application filed January 27, 1914. Serial No. 814,787.

To all whom it may concern:

Be it known that I, VINCENZO LOMBARDI CERRI, a subject of the King of Italy, and residing at Piazza Torlonia, Palazzo proprio, Avezzano, Province of Aquila, Italy, have invented certain new and useful Improvements in Sound-Proof Cases for Type-Writing Machines, of which the following is a specification; reference being had therein to the accompanying drawing.

My invention relates to a device to be applied to typewriting machines of any kind, for the purpose of deadening the noise thereof when they are operated upon.

According to my invention, the typewriting machine is inclosed within a case wadded with felt or other sound-deadening material, its key-board portion only remaining outside the case, and means are provided for rendering the machine visible and for returning the carriage carrying the platen of the machine, from the outside of the case, also for permitting an easy access to the machine and of its being readily taken out of, and placed into, the case.

With these objects in view, I provide the suitably shaped and conveniently sized case with a glass shutter arranged to be readily opened and being preferably cylindrical in shape, and I fasten this shutter to two oppositely disposed counterweighted rocking members respectively arranged near one side wall of the case, so that the shutter may be easily moved and friction is avoided. I return the carriage carrying the platen of the machine from the outside of the case by means of a train of levers, of which the first one acts on the return mechanism and the last one is disposed outside the case so as to project beyond the front edge thereof.

In order that my invention be readily understood, the same will here be described, by way of example, in one of its constructional forms, reference being had to the annexed drawings, in which—

Figure 1 is a cross section of the case, Fig. 2 a front elevation thereof, partly in section, and Fig. 3 a plan view, partly in section.

The sound-proof case according to the invention comprises a case or box 1, whose bottom 2 has a projecting front portion for supporting the key-board part of the machine, this projecting front portion extending slightly beyond the front part 3 of the frame of the machine, as it is shown in Fig.

1. The front wall of the case has an opening for placing the typewriting machine into the case, and a sliding shutter 4 is provided for closing this opening above the key-board portion projecting from the case. Between this shutter 4 and the upper part 5 of the case is an opening in the front wall, and the side walls 6, 7 are rounded along this opening. In each side wall is rotatably mounted a disk 8, for example, of wood, provided with a counterweight 9, and to these disks is fastened a cylindrically bent glass plate 10 adapted to close the opening between the parts 4 and 5, and connecting the two disks. This glass shutter may be opened and closed by rotating it around the journals of the disks 8 by means of a finger-piece 11. In this way, and through the arrangement of parts here provided, the glass shutter may not only be easily rotated, but may also be made to remain in any desired position, whether this be the open, the closed or an intermediate position. The box is wadded inside with pieces 12 of felt or other sound-deadening material, and also the disks 8 and the projecting portion of the bottom 2 are lined with the same material.

In order to return the carriage of the machine from the outside of the case, there is provided the following device. A vertically disposed shaft 13 turning in bearings, such as 14, arranged within the case, has fastened to it a horizontal lever 15 which is shaped so as to engage the pawl 16 provided in type-writing machines for returning the carriage carrying the platen. The lever 15 ends in a fork 17 in order to engage the said pawl. The shaft 13 passes through the bottom of the case to the outside thereof and has fastened to its projecting end a lever 18 which extends beyond the projecting front portion of the bottom 2 and ends in a handle 19.

The pawl 16 carried by the carriage of the type-writing machine and engaged by the fork 17, displaces the lever 15 when the carriage is successively fed from right to left during the operation of the machine, so that the shaft 13 is rotated and the lever 18 displaced. In order to return the carriage, it is sufficient to operate the handle 19 in the same manner as the pawl 16 would be operated in a machine not inclosed within the silencing case.

The manner in which the fork 17 and the pawl 16 are connected permits of the ma-

chine being easily taken out of the case, without any special manipulations being required.

What I claim is:

- 5 1. In a sound proof case for typewriting machines, the combination of, a box wadded with sound deadening material and adapted to inclose the machine except the key-board portion thereof; means for rendering the machine accessible and for removing it and replacing it; and means manipulated from the outside of the case for returning the carriage of the machine.
- 10 2. In a sound proof case for typewriting machines, the combination of, a box; and a shutter therefor comprising two oppositely disposed counter weighted disks rotatably

mounted in the side walls of the case, and a cylindrically bent glass plate fastened to said disks.

- 20 3. In a sound proof case for typewriting machines, the combination of, a box; a vertical shaft passing to the outside of the box; a forked lever on said shaft and adapted to engage the pawl of the typewriting machine; and a handle mounted on the projecting portion of said shaft.

In testimony whereof I have signed my name in the presence of two subscribing witnesses the 7th day of January 1914.

VINCENZO LOMBARDI CERRI.

Witnesses:

GIOVANNI VALATELLI.
CORELLA FORBANI.

It is hereby certified that the name of the patentee in Letters Patent No. 1,111,477, granted September 22, 1914, for an improvement in "Sound-Proof Cases for Type-Writing Machines" was erroneously printed in the heading to the drawing as "V. L. Cerri" whereas said name should have been printed as *V. Lombardi Cerri*; and that the said Letters Patent should be read with this correction therein that the same may conform to the record of the case in the Patent Office.

Signed and sealed this 23rd day of March, A. D., 1915.

[SEAL.]

J. T. NEWTON,

Acting Commissioner of Patents.
